UNITED STATES PATENT OFFICE.

JOSEPH BOURDAS SMITH BOOTH, OF SIDCUP, ENGLAND.

CARBURETER.

1,070,394.

Specification of Letters Patent. Patented Aug. 19, 1913.

Application filed March 24, 1913. Serial No. 756,424.

To all whom it may concern:

Be it known that I, JOSEPH BOURDAS SMITH BOOTH, residing at Sidcup, in the county of Kent, England, have invented certain new and useful Improvements in Carbureters; and I do hereby declare the following to be a full, clear, and exact description of the invention, such as will enable others skilled in the art to which it appertains to make and use the same.

This invention relates to apparatus for the carburation of air for lighting, heating and motive power purposes.

It has been found in practice that the greater the consumption of gas, the poorer the mixture becomes, and an air distributor adapted to give a correct mixture for a certain demand of gas, will not readily give a correct mixture for an increased demand.

The principal object of this invention is to provide a means whereby the correct quality of the mixture is maintained irrespective of the demand made on the carbureter for the said mixture.

Referring to the drawings:—Figure 1 is a side elevation of a carbureter with the side removed, made in accordance with this invention. Fig. 2 is a plan view with the cover removed. Fig. 3 is an inverted plan of part of the distributor. Fig. 4 is a section on line A—B. Fig. 3. Fig. 5 is a cross-section, taken on the line C—D in Fig. 4.

A fuel chamber *a*, formed of galvanized sheet iron, or other suitable material is provided with a cover *b*, held in position by suitable nuts *c* and bolts *d*. An inlet pipe *e*, connected preferably to a suitable supply of compressed air, conducts the compressed air to a distributor *f* composed of a series of inverted U tubes *g* open on their under side.

The tubes *g* have their ends closed by end walls *h* and *j*, but are in communication one with the other by a header *k* at one end of them. This header *k* is trough-shaped in cross-section, and it depends from a pipe section *e'* which forms a continuation of the inlet pipe *e*. A hole *l* is formed in the underside of the pipe section *e'* for placing it in communication with the header *k*. Also

located in the fuel chamber is a float chamber *m* preferably carried on the side of the chamber *a*. This chamber is entirely closed except at its under side, which is open to the fuel in the chamber *a* and always submerged by it. An auxiliary air pipe *n* communicating with the pipe *e*, supplies com-

pressed air to the upper side of the float chamber *m*, the pressure in the distributor *f* and chamber *m* always therefore being equal. Within the float chamber *m* is located a float *p* preferably formed of a hollow ball adapted to float upon the hydrocarbon in the chamber *m*, while outside the chamber is a second and similar float *o* adapted to float upon the liquid in the chamber *a*. These floats are both pivotally connected to a rod *q* which is itself pivotally connected to a valve rod *r*. The floats *o* and *p* can see-saw about the rod *r* without causing a movement to the rod, but should the respective levels of the liquid in the chambers *a* and *m* sink, the float end of the rod *r* will likewise sink and turn the rod *r* about a pivot *s* carried by a suitable bracket *t*, secured to the base of the chamber *a*. The end of the rod *r*, remote from the floats, will therefore rise and lift a valve *u*, suitably pivoted to and at the end of the rod *r*, from its valve seat *v* and admit fuel to the chamber *a* through the inlet *w*.

The air pipe *e* is provided with swivel joints at *x* and *y*, and with an eye *z* secured to the pipe. A second eye *1* is secured to one of the tubes *g*. The eye *z* is linked to a rod *2* which is screwed at *3* and passes through the cover *b*; an adjusting nut *4* being adapted to take onto the screw *3*. The eye *1* is likewise linked to a similar rod *5* screwed at *6*, upon which screw is an adjusting nut *7*.

An outlet main *8* is provided for conveying away the gas from the upper portion of the chamber *a* to a suitable storing container, or direct to a supply system.

A screw stopper *9* may be provided in the cover *b* for replenishing the chamber *a* with liquid, in addition to the pipe *w*.

A gage for visibly ascertaining the amount of fuel in the chamber *a* may be provided, and may consist of a gage glass *9'*, having communication with the chamber *a* above the fuel level at *10* and below the fuel level at *11*.

In operation, the inlet *e* of the carbureter is suitably connected up to a supply of air under pressure. The main *8* is connected to a gas receiver or supply system, while the inlet pipe *w* is in communication with a liquid fuel supply. It will be observed that the distributor *f* can turn about the joint *y* of the pipe *e* in such a manner that if the rod *5* is screwed upward by the nut *7* the end of the distributor *f* beneath it will be

raised, and if the rod 5 is lowered, the end of the distributor will also be lowered. Likewise the other end of the distributor can be raised by the rod 2 and nut 4, when the pipe *e* will turn about the joint *a*. When air is admitted to the inlet, it passes along the pipe *e*, through the aperture *l* into the distributor tubes *g*. It then passes through or over the liquid, carrying volatile vapor with it to the upper portion of the chamber *a*. The mixture then passes away by the main *s* to a container or supply system. The area through which the air passes into the hydrocarbon is decreased or increased, in accordance with the difference in pressure between the inside and the outside of the distributor *f*, owing to the inclination of the distributor, which is varied at will. The auxiliary pipe *n* supplies compressed air directly from the pipe *e* to the float chamber *m*; it will therefore be manifest that the pressure on the surface of the liquid in *m* will be the same as that on the liquid in the tubes *g*. But the pressure on the surface of the liquid outside the chamber *m* and tubes *g* will be less than that in the chamber and tubes; therefore the level of the liquid in the chamber and tubes will vary in the same ratio to the level outside the chamber *m* and tubes *g*; as do the pressures within and without the chamber and tubes. Consequently the float *p* will be lower, when compressed air is being supplied to the carbureter, than the float *o*, and the bar *q* will have assumed an angular position relatively to the horizontal plane, but no motion will have been imparted to the valve rod *r*. If however, the mean level of the liquid falls, owing to the volatilizing of the liquid, both floats will move downward, and the valve rod *r*, operated by the rod *q*, will lift the valve *w* and admit more liquid to the chamber *a*.

The combined dimensions of the float chamber *m* and distributor *f* should be such that the superficial area of the liquid within them is approximately equal to the superficial area of the liquid contained by the chamber *a*. The rod *q* should be pivoted at its center to the valve rod *r* so that the floats balance, or substantially do so, when not influenced by the liquid. In case the superficial areas of the liquids do not coincide with one another, the pivot connecting the rod *q* to the valve rod *r*, may be made adjustable so that the floats may be adapted to suit any inequality in the areas.

If desired, suitable means may be employed for heating the carbureter.

It will be clear that should the demand for mixture be great, the pressure in the main *s* and upper portion of the chamber *a* will be reduced, and consequently the level of the fuel in the chamber *a* will rise. This rising of the fuel in the chamber *a* is ac-

companied by a corresponding fall of fuel in the tubes *g*, thereby increasing the area of escape of the air through the fuel. Consequently the compressed air in the distributor will have more fuel to bubble through and consequently the mixture will be maintained in quality. Should the converse happen, and the demand for mixture be decreased, a resulting increased pressure in the main *s* and chamber *a* will take place, and the fuel level in the chamber *a* will sink; thus an accompanying rise in the tubes *g* and chamber *m* will take place, and therefore a lessening of the area and bulk of fuel through which the air passes. Thus it will be seen that supposing for instance, the carbureter is being used in connection with a petrol lighting system, the carbureter will automatically maintain the quality of the mixture irrespective of the number of burners lighted in the system.

I claim:—

1. A carbureter comprising a mixture chamber; a distributor formed of U shaped tubes, open on their under side; means for supplying compressed air to said distributor; a mixture outlet from said mixture chamber; a fuel inlet to said mixture chamber; a valve controlling said fuel inlet and means for operating said valve according to the mean level of the fuel in said mixture chamber and said distributor.

2. A carbureter comprising a mixture chamber; a distributor formed of U shaped tubes open on their under side; means for supplying compressed air to said distributor; a mixture outlet from said mixture chamber; a fuel inlet to said mixture chamber; a valve controlling said fuel inlet; a float located in said mixture chamber; a float located in a float chamber, said float chamber being adapted to be supplied with compressed air at the same pressure as said distributor, and means for operably connecting said floats to said valve.

3. A carbureter comprising a mixture chamber; a distributor formed of U shaped tubes open on their under side; means for supplying compressed air to said distributor; a mixture outlet from said mixture chamber; a fuel inlet to said mixture chamber; a valve controlling said fuel inlet; a float located in said mixture chamber and connected to one end of a bar; a float located in a float chamber supplied with compressed air at the same pressure as said distributor; said float being connected to the other end of said bar; a lever pivotally connected to said bar at one end, and pivotally connected to said valve at the other end, and adapted to turn about a pivot so as to raise and lower said valve.

4. A carbureter comprising a mixture chamber; a distributor formed of U shaped tubes open on their under side; a pipe for

supplying compressed air to said distributor; means for raising and lowering said distributor in said mixture chamber; a mixture outlet from said mixture chamber; a 5 fuel inlet to said mixture chamber; a valve controlling said fuel inlet; a spherical float located in said mixture chamber; and connected to one end of a bar; a spherical float, connected to the other end of said bar, and 10 located in a float chamber; a pipe for conducting compressed air to said float chamber from said distributor pipe; a lever

pivotal and adjustably connected to said bar at one end, and pivotally connected to said valve at the other end, and a bracket 15 carrying a pivot about which said lever is adapted to turn.

In testimony whereof I have affixed my signature, in presence of two witnesses.
